[57] CLAIM

The ornamental design for hospital brief, as shown and described.

DESCRIPTION

FIG. 1 is a front elevational view of a hospital brief showing my new design;

FIG. 2 is a rear elevational view thereof;

FIG. 3 is a front elevational view thereof, the front panel being unfastened and lifted;

FIG. 4 is an inside elevational view thereof, the garment shown open and spread flat; and,

FIG. 5 is an outside elevational view thereof; the garment shown open and spread flat.

The broken lines shown throughout the views are understood to represent conventional stitching.

FIG. 1

FIG. 2

FIG. 3

FIG. 4

FIG. 5
